UNITED STATES PATENT OFFICE.

OTIS D. WELSCH, OF KIMBERLY, NEVADA.

PROCESS OF AND APPARATUS FOR ORE CONCENTRATION.

1,253,653.

Specification of Letters Patent. Patented Jan. 15, 1918.

Application filed May 26, 1917. Serial No. 171,229.

To all whom it may concern:

Be it known that I, Otis D. Welsch, a citizen of the United States, residing at Kimberly, in the county of White Pine and State of Nevada, have invented certain new and useful Improvements in Processes of and Apparatus for Ore Concentration, of which the following is a specification, reference being had to the accompanying drawings.

This invention relates to a process of ore concentration and ore concentrators, and particularly to concentrators operating on the flotation principle described in Patent No. 835,120, granted on the 6th of November, 1906.

In concentrators of this type and operating on this principle, the ore in a finely pulverized state is mixed with water and oil and usually with a certain amount of acid added. The pulp thus formed is agitated by suitable heaters, so as to cause a froth to rise to the surface of the mass which is composed of air bubbles with only a trace of oil in them, these bubbles being of a peculiarly coherent and persistent character and carrying in mechanical suspension a very high percentage of the metal and metalliferous particles of ore which are contained in the mass of crushed ore or pulp submitted for treatment. This froth is removed and the metal recovered by suitable processes to that end. This froth, although very light, and composed of relatively easily destructible air bubbles, has its air bubbles covered with heavy mineral. The froth, however, is stable and is relatively permanent in character.

As before stated, heretofore this froth has been formed by agitating the pulp by means of paddles or like mechanical devices and the general object of this invention is to improve upon the means for securing this froth by injecting compressed air into the spitzkasten, the air being carried down to the bottom of the spitzkasten and being thoroughly intermingled with the pulp therein, the bubbles of air rising to the surface in the form of froth as heretofore described.

A further object of the invention is to provide an air collecting chamber into which the compressed air is caused to rise through the pulp and provide means whereby the

air within this chamber may be adjusted to the right degree of pressure to produce a proper floatative froth when the air in the chamber is allowed to escape into the spitzkasten.

Other objects will appear in the course of the following description.

My invention is illustrated in the accompanying drawings, wherein:

Figure 1 is a vertical section through a concentrator constructed in accordance with my invention;

Fig. 2 is a top plan view thereof;

Fig. 3 is a longitudinal sectional view thereof.

Referring to these drawings, it will be seen that my improved mechanism is extremely simple. It comprises a separating compartment or spitzkasten, designated 10, which as illustrated, is gradually contracted toward its lower end and which is provided with a feed inlet 11 at one end and a tailing outlet 12 at the other end. Extending into the separating compartment or spitzkasten 10, nearly to the bottom thereof, is a compressed air inlet pipe 13 provided with a valve 14 or other suitable means for controlling the inlet of air. This pipe 13 is connected to a reservoir of compressed air or to a compressed air pump. I have indicated on the drawing a reservoir of compressed air, but it will be understood that any means for securing a compression of air and an injection of this compressed air through the pipe 13 is within the scope of my invention.

Surrounding the air pipe 13 is a chamber 15 closed at its upper end, open at its lower end and extending down into the spitzkasten, but spaced above the lower end of the pipe and relatively near to the surface of the pulp contained within the spitzkasten. Surrounding the lower portion of the air pipe and extending upward into the chamber 15 is an air lift chamber 16, which is open at its upper and lower ends. This air lift chamber 16 is spaced from the chamber 15 and extends above and below the lower edge of this chamber 15, so that the portion of the chamber 15 which projects down below the upper end of the chamber 15, constitutes a baffle wall. Mounted upon the pipe 13, above the upper end of the chamber 16, but contiguous thereto, is a

hood 17 which extends downward and outward, so that the pulp which is drawn upward through the chamber 16 will strike this deflector 17 and be diverted downward and outward into the chamber 15.

Means may either be provided for controlling the amount of air ejected from the pipe 13 and therefore the force with which the air is ejected from the pipe 13 and the degree of compression within the chamber 15, or the chamber 15 may be provided with a valve which will control the degree of compression of the air within the chamber 15. In Fig. 1, I have illustrated a valve 19 for this purpose. The chamber 15 at its upper end is provided with an opening 18 and a slide valve 19 is suitably mounted upon the upper end of the chamber, so as to extend partially over said opening. In Fig. 1, I also show a valve whereby the amount of air introduced into the machine by the pipe 13 may be controlled.

In the drawing I have illustrated a spitzkasten which is rectangular in plan, a chamber 15 which is elongated and has the same length as the spitzkasten, and I have illustrated two air inlet pipes 13 and an air lift chamber, which extends the full length of the chamber 15. I do not wish to be limited to this, however, as the machine can be built along rectangular lines, or circular in shape, without involving any difference in principle or operation. Any number of air pipes may be used and, of course, any number of chambers 16 surrounding the air pipes. Neither do I wish to be limited to the particular location of the baffle 17, to the particular form of this baffle, or to the particular form of the valve controlling the pressure in the casing 15. It is also obvious that the casing 15 might be modified in form, without departing from the spirit of the invention.

In the practical use of this invention, the modified pulp is introduced into the machine through the opening 11 and air is introduced into the machine through the pipe 13. The compressed air escaping from the lower end of the pipe 13 will not escape below the lower end of the chamber 16, but will rise up within this chamber and with such force as to agitate and lift the pulp within the chamber, thus causing the circulation of the pulp. The pulp will be raised and will discharge over the side walls of the chamber 16 and then pass downward beneath the depending walls of the chamber 15, which constitute baffle walls and then pass into the spitzkasten 10. It will be seen that a certain amount of air will be trapped within the chamber 15 and this trapped air will exert a downward pressure on the pulp so as to cause it to pass beneath the baffle walls 15^a. It will be seen that the air, after accomplishing its purpose of lifting the pulp in the chamber 16, ac-

cumulates in the chamber 15, where it tends to serve a further function, that is to develop or form a mineral froth by the passage of the mixed air and pulp downward from the lower end of the chamber 15 into the spitzkasten 10. This frothing in the separating compartment or spitzkasten 10 can best be accomplished by adjusting the pressure of air in the chamber 15 in some manner, as by means of the valve 19 and opening 18, or by controlling the amount of air introduced into the machine by means of the air pipe for the air lift. I find in practice that this manner of intimately combining the air with the pulp results in a much better and quicker intermingling of the air with the pulp than where the air is beaten into the pulp by agitation and that the froth is formed in a much quicker time than would otherwise be the case with no tendency to break up the air bubbles which rise to the surface to form the froth.

The compressed air, as it passes upward from the lower end of the pipe 13, lifts and agitates the pulp in the compartment 16 and escapes into the chamber 15. It will collect in this chamber 15 until pressure is developed in this chamber to such a degree that the air is forced down below the baffle walls 15^a into the spitzkasten or separator 10. If all of the air is allowed to escape this way, however, that is downward beneath the baffle wall 15^a and if at the same time enough air passes through the air line pipe 13 to accomplish the purpose of agitating and lifting the pulp in the compartment 16, then the disturbances in the spitzkasten caused by this escaping air would be too great and would have an injurious effect upon the froth forming on the surface of the pulp in the spitzkasten. It is for this reason, therefore, that I allow enough air to escape from the chamber 15 through the adjustable opening, as will prevent this too great agitation in the spitzkasten and so that the bubbles of air passing up through the pulp in the spitzkasten will build up a mineral bearing froth. It will be seen that the air entering through the pipe 13 acts as an air lift lifting up the pulp in the column defined by the compartment 16 and then passing downward through the lower end of the chamber 15 and the bubbles then rising relatively quietly up through the pulp to the top where they accumulate as froth. If the compressed air were allowed to pass immediately out through the pipe 13 into the spitzkasten, the effect would be to break up the froth.

My invention is an improvement over those referred to in the first paragraph of this specification in which the agitating is secured with paddles, because paddles or like agitators involve wear and tear and hence increased cost of upkeep. In this

machine the item of upkeep is relatively low as there is no wear and tear on any of the working parts, and the oil and mineral pulp are thoroughly mixed by the circulation of the oil and mineral caused by the uprushing column of air and oil and mineral in the compartment 16. I am aware of the fact that in the Callow machine a porous medium is used through which air is forced, but my construction has an advantage over this in that there are no parts which must be changed because of usage. In this Callow type of machine the porous medium becomes defective because its openings become clogged with dirt, oil, etc., and hence the medium cannot perform its proper function. Also oversized particles in the pulp accumulate on the porous medium and this prevents the pneumatic type of machine from doing its work properly and necessitates frequent cleaning and the porous medium must be replaced quite frequently. Furthermore, the first cost of constructing a machine in accordance with my invention is relatively low compared with other types. The cost of operation is also relatively low and this is particularly important where concentration of low grade ore is being carried out.

It is to be understood that there should be no froth formed in any compartment except in the spitzkasten 10. The air will rise to the air collecting chamber through the pulp, then when the desired pressure is obtained in the chamber 15, it will compel compressed air to enter the compartment 10 or spitzkasten and assist in floating the mineral particles.

It will be understood that the uprising column of compressed air does not cause any frothing within the casing 16, but acts as an air lift and keeps the pulp in circulation, that is, the pulp returns to the lower end of the casing 16 and rises again and again and so gets continuous treatment until discharged through the gangue discharge 12. This lifting of the pulp and the striking of the pulp against the deflector 17 causes agitation and the bubbles formed by the compressed air escape under the baffle walls 15^a and cause the froth to form in the spitzkasten. The compressed air which is used for lifting the pulp collects in the space above the pulp, that is, in the chamber 15 until a pressure is developed which will force this air out beneath the walls 15^a whereupon the bubbles of air rise to the surface of the spitzkasten and form a froth, but unless the pressure within the chamber of the spitzkasten is regulated, good results will not be secured. Too much air escaping through the passage 18 prevents any bubbles forming in the spitzkasten and if the opening 18 be closed entirely, all of the air from the chamber 15 is forced into the spitzkasten. This causes large bubbles, which cause

any fragile bubbles in the froth to burst and furthermore these large bubbles are very fragile, but by adjusting the pressure in the chamber 15, I secure the proper results. It will be obvious that the pressure within the chamber 15 may be varied by having a constant area of opening 18 and varying the pressure of the compressed air or by keeping the pressure of the compressed air constant, but varying the opening 18.

Having described my invention, what I claim is:—

1. An ore concentrator operating on the flotation principle including a spitzkasten to contain the pulp and having a froth discharge and a gangue discharge, and means for frothing the pulp comprising means for discharging compressed air below the surface of the pulp, an air chamber open at its lower end and extending into the spitzkasten below the level of the pulp and into which chamber the compressed air rising through the pulp discharges, and means for controlling the pressure of air in said chamber.

2. In an ore concentrator operating on the flotation principle, a spitzkasten to contain the pulp having a froth discharge and a gangue discharge, and means for frothing the pulp, comprising a compressed air pipe extending into the spitzkasten below the level of pulp therein, an air lift chamber open at its upper and lower ends and into which the compressed air pipe discharges, the lower end of the air lift chamber extending below the lower end of the air pipe, and an air chamber closed at its upper end and extending into the spitzkasten around and below the level of the upper end of said air lifting chamber.

3. In an ore concentrator operating on the flotation principle, a spitzkasten to contain the pulp having a froth discharge and a gangue discharge, and means for frothing the pulp, comprising a compressed air pipe extending into the spitzkasten below the level of pulp therein, an air lift chamber open at its upper and lower ends and into which the compressed air pipe discharges, the lower end of the air lift chamber extending below the lower end of the air pipe, an air chamber closed at its upper end and extending into the spitzkasten around and below the level of the upper end of said air lift chamber, and means for regulating the pressure of air within said chamber.

4. In an ore concentrator operating on the flotation principle, a spitzkasten to contain the pulp having a froth discharge and a gangue discharge, and means for frothing the pulp comprising a pipe connected to a source of compressed fluid and extending downward into the spitzkasten nearly to the lower end thereof, an air lift chamber sur-

rounding said pipe and open at its upper and lower ends and extending slightly below the air pipe, an air chamber surrounding the air lift chamber, closed at its upper end, open at its lower end and extending below the top of the air lift chamber, and a pressure controlling valve in the top of said air chamber.

5. In an ore concentrator operating on the flotation principle, a spitzkasten to contain the pulp having a froth discharge and a gangue discharge, and means for frothing the pulp comprising a pipe connected to a source of compressed air and extending down into said spitzkasten below the level of the pulp therein, an air lift chamber open at its upper and lower ends surrounding said pipe and extending below the lower end of the pipe, an outwardly and downwardly extending deflector disposed above the upper end of the air lift chamber, an air chamber closed at its upper end extending downward and surrounding the air lift chamber but spaced therefrom and open at its lower end, the lower edge of said air chamber being disposed below the upper end of the air lift chamber, and means for controlling the pressure of air within said air chamber.
- 30 6. In an ore concentrator operating on the flotation principle, a spitzkasten to contain the pulp having a froth discharge and a gangue discharge, and means for frothing the pulp comprising a pipe connected to a source of compressed air and extending down into said spitzkasten below the level of the pulp therein, an air lift chamber open at its upper and lower ends surrounding said pipe and extending below the lower end of the pipe, an outwardly and downwardly extending deflector disposed above the upper end of the air lift chamber, an air chamber closed at its upper end extending downward and surrounding the air lift chamber but spaced therefrom and open at its lower end, the lower edge of said air chamber being disposed below the upper end of the air lift chamber, and a valve in the air chamber controlling the outlet of air therefrom and thereby controlling the pressure within the chamber.
7. In an ore concentrator operating on the flotation principle, a spitzkasten having a feed opening, a froth discharge, and a gangue discharge opening and containing the pulp to be treated, and means for frothing the pulp comprising a plurality of pipes connected to a source of compressed air and extending down into the pulp to be frothed, an air chamber closed at its upper end and inclosing said pipes, the sides of the air chamber extending down into and below the level of the pulp, and means for controlling the pressure of air within said chamber.
- 65 8. In an ore concentrator operating on

the flotation principle, a spitzkasten for containing the pulp and having a froth discharge, a feed opening and a gangue discharge opening, a plurality of compressed air pipes extending into said spitzkasten nearly to the bottom thereof and connected to a source of compressed air, an air lift chamber open at its top and bottom and having walls extending parallel to but spaced from said series of pipes and extending down below the pipes, a deflector mounted above the open upper end of the air lift chamber, and an air chamber having side walls extending down into the spitzkasten and terminating above the lower end of the air lift chamber, said air chamber being closed at its upper end and the walls being spaced from the walls of the air lift chamber, and means for controlling the air pressure within the air chamber.

9. In an ore concentrator operating on the flotation principle, a spitzkasten for containing the pulp and having a froth discharge, a feed opening and a gangue discharge opening, a plurality of compressed air pipes extending into said spitzkasten nearly to the bottom thereof and connected to a source of compressed air, an air lift chamber open at its top and bottom and having walls extending parallel to but spaced from said series of pipes and extending down below the pipes, a deflector mounted above the open upper end of the air lift chamber, and an air chamber having side walls extending down into the spitzkasten and terminating above the lower end of the air lift chamber, said air chamber being closed at its upper end and the walls being spaced from the walls of the air lift chamber, and means for controlling the air pressure within the air chamber, said means comprising an adjustable valve mounted upon the top of the air chamber.

10. An ore concentrator operating on the flotation principle including a spitzkasten to contain pulp and having a froth discharge and a gangue discharge, and means for frothing the pulp comprising means for discharging compressed air at a predetermined pressure below the surface of the pulp, an air chamber open at its lower end and extending into the spitzkasten below the level of the pulp and into which said compressed air discharges as the compressed air rises through the pulp, and means for reducing the pressure of the air collected within said chamber below the pressure of the compressed air as it enters the pulp, the compressed air in said chamber at said reduced pressure acting to force the pulp downward beneath the lower edge of the chamber and upward through the pulp exterior to the chamber.

11. A method of concentrating ore consisting in discharging air under pressure

into a body of mineral pulp below the surface thereof and within a confined space to thereby cause an ascending column of compressed air and pulp and to thereby cause the agitation of the pulp within said space, and then causing air under less pressure to pass downward through and with the agitated pulp into the main body of pulp to thereby form air bubbles within the main

body of the pulp, and a froth upon the surface of the pulp.

In testimony whereof I hereunto affix my signature in the presence of two witnesses.
